SPARK PLUGS

István Szilágyi, Budapest, Hungary, assignor to "Licencia"
Tárlatmányokat Értékesítő Vállalat, Budapest, Hungary

Application July 11, 1950, Serial No. 173,046

Claims priority, application Hungary July 20, 1949

3 Claims. (Cl. 313—132)

The invention relates to spark plugs for internal combustion engines and particularly to the structure and disposition of spark plug electrodes, whereby fouling of the spark plug by carbon is minimized.

The primary object of the invention is the provision of a slit in at least one of the electrodes of the spark plug, the width of this slit being smaller than the length of the spark gap between the coating electrodes. Thus due to capillary attraction oil particles will be preferentially caught in the said slit rather than in the gap between the coating electrodes.

Another object of the invention is the provision of the spark points of the electrodes in or near the smallest cross section of a bore arranged in the lower part of the body of the spark plug, this bore having preferably the shape of a Laval-tube, i. e. having at one place a restricted cross section enlarging in both directions outward from the said restricted cross section.

A further object of the invention is the provision of an insulating, tube shaped body, surrounding the center electrode and spaced from this electrode so as to form an annular space communicating with the restricted bore in the lower part of the spark plug and tightly closed at its upper end. The diameter of the center electrode is thus less than the inner diameter of the tube shaped body and during the compression stroke the gas penetrates through the said bore into the tube shaped insulator, while during the explosion stroke the gas flows in an opposite direction. As the velocity of the gas is the highest in the cross section of the said bore where the spark points are located, the rapid gas stream removes the oil drops caught in the slit of the electrodes at each stroke.

Other features of the invention will be apparent to one skilled in the art from the following description taken in connection with the annexed drawings, wherein—

Fig. 1 is a longitudinal central sectional view of a spark plug embodying the features of the present invention.

Fig. 2 is a bottom plan view of the spark plug of Fig. 1.

Fig. 3 is a side view of the spark plug according to Fig. 1.

Fig. 4 is a longitudinal central sectional view of another embodiment of the invention.

Fig. 5 is a bottom plan view of the spark plug of Fig. 4.

Fig. 6 is a side view of the spark plug according to Fig. 4.

Fig. 7 is a side and partly a sectional view showing a slight modification of the construction of Figs. 1-3.

Fig. 8 is a plan view of the spark plug of Fig. 7.

The preferred form of my improved spark plug is shown in Figs. 1-3. In these figures the reference character 1 indicates the lower part of the shell of a spark plug, provided with the usual thread 2. Passing centrally through a bore 3 in this part is the center electrode 5 secured at its upper end in a cylindrical shaped body 4. Between this body 4 and the lower part 1 of the spark plug a tube shaped hollow member 6, preferably of

5 vitreous silica is provided, the diameter of the electrode 5 being smaller than the inner diameter of the insulating member 6. Thus the center electrode is placed in a space 7 communicating with the bore 3 in the lower part of the spark plug. The tube shaped insulating member is on its upper end tightly closed by means of a sealing ring 8 and the body 4, provided with cooling fins 10. This body 4 is arranged between the tube shaped silica member 6 and a centre cap 11. Member 6, body 4 and centre cap 11 are fixed in the shown position by a bridle 12 pivotally mounted in the lower part 1 of the spark plug, whereby the pressure exercised by the bridle may be adjusted by means of a screw 13 fitted in the centre cap 11 and having a groove 15 in its head 14 in which the upper part of the bridle 12 is located. The legs of the bridle 12 are both provided with an insulating covering 16.

10 The bearing body 4 is made of a conducting material, the centre cap 11 of an insulating material, whereby the body 4 serves as a binding nut for proper connection with the external wiring system.

15 The lower part 1 of the shell as usual, constitutes one pole of the electric circuit, an electrode 17 being mounted upon the shell. This electrode is arranged transversally to the geometrical axis of the bore 3 and comprises two rods 17a and 17b parallel to one another and forming a narrow slit 18, the width of this slit 18 being smaller than the length x of the spark gap between the coating electrodes 5 and 17. Thus, oil drops are caught by capillary attraction in the slit 18 rather than in the gap x, where they would foul the plug.

20 In order to remove the oil drops or other deposits out of the slot 18 the bore 3 is shaped like a Laval tube and the spark gap is arranged in the narrowest cross section of the bore. As this bore 3 communicates with the space 7 inside the silica member 6, gas flows into this space 7 through the bore 3 during the compression stroke and flows out during the expansion stroke. The spark points being located in the narrowest cross section of the bore the rapid flowing stream of gas acts as a thoroughly effective cleaning means, blowing the oil drops out of the slit between the electrodes 17a and 17b. At the same time the pressure of the gas being the lowest around the spark gap the electric resistance in the spark gap is diminished.

25 The construction shown in Figs. 1, 2 and 3 may be modified as shown in Figs. 4, 5 and 6 for the purpose of a radio shielded spark plug. The centre electrode 18 is mounted in a mica ring 19, located between two tube shaped, insulating members 20 and 21 made of transparent material such as quartz. The center electrode passes through the whole height of the mica ring 19 for proper connection at its upper end with the external wiring system. The grounded electrode consists of four parts 22a—22d spaced from one another by slits 0. In each of these electrodes a slit 23 is provided, whereby the width of each of the slits 0 and 23 is smaller than the length x of the spark gap. This gap is arranged in the smallest cross section of the bore 24 formed like a Laval tube.

30 Openings 28 covered by wire gauze 27 are provided in the metal shell or bushing 29 of the spark plug and thus the flame can be observed from the outside.

35 The grounded electrode of the spark plug may also be made as a single electrode, whereby the slit is arranged in the neighbourhood of the spark point.

40 In the slightly modified form shown in Figs. 7 and 8 both the center electrode 25 and the grounded electrode 26 are slotted. The outer parts of this spark plug are like those shown in Figs. 1-3.

45 The invention claimed is:

1. A spark plug comprising a shell, an insulated center

electrode, a grounded electrode formed of two straight parallel rods extending diametrically across the lower end of the shell and spaced transversely of the shell to form a narrow slit between them of a width less than the length of the spark gap between said center and grounded electrodes.

2. A spark plug according to claim 1 in which the shell has an axial bore therein, the diameter of said bore varying along the axis of the bore and the spark points of the electrodes being located in the narrowest section of the said bore.

3. A spark plug comprising a shell, a hollow tubular member of insulating material, a conductor having a diameter less than the internal diameter of said tubular member and passing through the said member and forming a center electrode, a grounded electrode formed of two straight parallel rods extending diametrically across the lower end of the shell and spaced transversely of the shell to form a narrow slit between them of a width less than the length of the spark gap between said center and grounded electrodes, said shell having an axially extend-

ing conical bore therein communicating at its region of greatest diameter with the interior of said tubular member, and the spark points of said electrodes being located in the region of said conical bore of smallest diameter.
